ELECTRICAL CONNECTOR

William Huppert, New York, N. Y.

Application December 14, 1944, Serial No. 568,094

3 Claims. (Cl. 173—334)

1

This invention relates to an electrical connector, and more particularly to an improved outlet of the type shown in my Patents Nos. 1,818,804 and 2,316,167, such as commonly used for making electrical connections between conducting wires or cords and a plurality of plugs, as well as for other purposes in the electrical art.

Among the objects of the invention are to provide a connector or outlet for use with three or more conventional plugs, preferably three, which is of minimum height and length, consists of only a few simple parts that are inexpensive to make and easy to assemble, that affords a good and reliable electrical connection between the plug blades and the contact fingers, and in which the contact members are firmly held in proper position.

Other objects and advantages of the invention will appear from the following description thereof. The drawings show the invention embodied in an outlet of the kind known in the trade as a "convenience" outlet but it may be applied to other forms of connectors, such for instance as taps.

In the drawings:

Figure 1 is a side view of an outlet with three plugs indicated in phantom;

Fig. 2 is a bottom plan view, on an enlarged scale, with the bottom closure plate mostly broken away;

Fig. 3 is a longitudinal vertical section on the line 3—3 of Fig. 2, the bottom plate being partly broken;

Fig. 4 is a transverse vertical section on the line 4—4 of Fig. 3 with the bottom plate partly broken; and

Fig. 5 is a longitudinal vertical section on the line 5—5 of Fig. 2.

The outlet comprises in general only four simple and easily assembled parts, namely, a housing 10, two similar contact members 11, and a detachable bottom closure plate 12. The outlet may be detachably fastened to a wooden base-board or other supporting surface 13 by a screw 14 or the like.

The housing 10 is preferably molded in one piece of Bakelite or other suitable insulating material, and it is so designed that it may be formed by a straight-line or vertical molding operation in a two part mold without any cores to pull. Its exterior contour has a flat top face 15, two inclined flat faces 16, end walls 17, and side walls 18. The faces 15 and 16 each have a pair of slots 19 leading into interior chambers 20 in which the contact members 11 are confined, and through which slots the blades 21 of conventional plugs 22 may enter to make electrical contact with the fingers 25 of the contact members. The housing may be formed with an exterior boss 23 extending lon-

gitudinally between the slots to facilitate proper placement of the plug-blades in the slots.

The outer contour of the housing viewed lengthwise, is characterized by the fact that it is so shaped or formed that all of its faces are tangential or substantially tangential to an inscribed semi-elliptical curve whose minor axis equals the height and whose major axis equals the length of the housing. This form provides a structure of minimum height and length to accommodate the desired number of plugs. While the particular structure illustrated and described herein is intended for use with three plugs it may be modified for use with more than three. The fact that the housing is of minimum height and length to accommodate the desired number of plugs is an important feature not only from the standpoint of compactness but also from those of economy of material and cost of production.

The contact members 11 each consist of a terminal portion 24 and diverging fingers or arms 25. They may be made of one piece of suitable metal in the manner of my Patent No. 2,248,675, or of more than one piece and in any other manner. As illustrated, the terminal position 24 is formed with teeth 26 for making electrical contact with the lead or conducting wires (not shown) although conventional binding screws may be used instead. For that purpose the housing may be formed with cavities 27 to receive the ends of such screws.

The chambers 20, in which the fingers 25 of the contact members are located, are defined by the spaced, parallel, longitudinal interior walls 28 and 29. The terminal portion 24 of each contact member seats on a correspondingly shaped cradle 30, one at each side of the center of the housing. As shown, each cradle may have a flat horizontal portion 31 and two inclined lateral portions 32.

In assembly, the contact members are placed in the housing with their terminal portions 24 fitting on the cradles 30 and their fingers 25 extending into the chambers 20 in position to make contact with the blades of the plugs when they are inserted in the slots. Vertical ribs or projections 33 may be provided to facilitate proper placement of the contact members during assembly and to prevent them from moving when inserted in place.

After the parts are assembled, the bottom plate 12 is placed in position. Abutments 34 may be formed in four corners of the housing against which the plate rests. On reference to Fig. 3 it will be seen that the two inclined contact fingers may be formed with straight lower edges 35 that bear on the inner surface of the plate to afford additional support of said fingers. An opening 36 extending vertically through the center of the housing, and a corresponding opening 37 in the

bottom plate, permit of passage of the fastening screw 14.

The housing has an opening 38 in one or both of its end walls for the lead or conducting wires, which wires make contact with the terminal portions of the contact members. Posts 39 may be provided, one at each side of each terminal portion, to guide the conductors into proper position for contact with the terminal portions, which posts may extend into openings or recesses 40 in the bottom plate, as described in my Patent 2,316,167.

It is to be noted, as illustrated in Fig. 1, that when the several plugs are attached to the outlet the lower ends of the inserted blades come closely together thus providing a very compact structure and permitting of use of a housing of minimum length to accommodate at least three plugs. It will also be seen that the housing is so designed that as the plugs 22 are being mounted on the inclined faces 16 the inner ends of their blades 21 will strike angularly against and slide upon the inner face of the closure plate 12 and will thus be guided into proper relation to make good electrical contact with the inclined contact fingers 25 when the blades are fully inserted.

The housing is formed with interior vertical walls or surfaces 41, 42 and inclined surfaces 43 adjacent to the blade receiving openings 19. This construction permits of molding the housing in one piece with a two part mold and without any cores to pull. In assembly, these surfaces serve to assist in guiding the contact fingers into proper position in relation to the blade receiving openings, and in use they serve to prevent the fingers from being accidentally displaced by the blades upon their insertion into the housing. For instance, on referring to Fig. 3 it will be seen that the center contact finger is confined between the vertical surfaces 41, and that the lower corners of the two inclined contact fingers come very close to the vertical surfaces 42. Consequently should either of these two fingers tend to be driven downward out of line by and with the plug-blades such tendency would be limited to an unobjectionable extent by the proximate surfaces 42.

The length of the housing 10 is greater than twice its height, and the distance from the center of the blade receiving slots or openings 19 in the top face 15 to the center of the detachable bottom closure plate 12 is less than the corresponding distance from the slots or openings in the lateral inclined faces 16. Furthermore, the two inclined contact fingers 25 are each preferably longer than the middle or vertical finger.

The free ends of the contact fingers are preferably curved slightly inward as shown. While in the drawings the contact fingers, for clearness of illustration, are shown spaced a short distance from the ribs 33, it is to be understood that in practice the ribs may be designed to lie directly against the contact fingers to assist in holding the contact members in place as hereinbefore described.

Various modifications in the details of construction herein described and illustrated in the drawings may be made by those skilled in the art within the scope of the invention as defined in the claims.

What I claim is:

1. An electrical connector for reception of a plurality of electrical plugs, comprising a housing of insulating material having openings for in-

sertion of the plug blades, a plurality of contact members located within said housing, each contact member having a terminal portion and a plurality of diverging spring fingers extending from the terminal portion in a plane substantially perpendicular to the plane of the terminal portion and leading from said portion toward the blade receiving openings, the two outer fingers extending at an angle to each other, and projections within the housing that bear against the spring fingers adjacent to their connection with the terminal portion to clamp the contact members firmly in place by spring tension between said projections and the adjacent inner surface of an exterior wall of the housing.

2. An electrical connector for reception of a plurality of electrical plugs, comprising a housing of insulating material having openings for insertion of the plug blades, a plurality of contact members disposed in the housing, each contact member having a terminal portion and a plurality of diverging spring fingers extending from the terminal portion in a plane substantially perpendicular to the plane of said terminal portion and leading from said portion toward the blade receiving openings, the two outer fingers extending at an angle to each other and having flared free ends, and projections within the housing that bear against said outer spring fingers adjacent to their connection with the terminal portion to clamp the contact members firmly in place by spring tension between said projections and the adjacent inner surface of an exterior wall of the housing, the angle between the two outer fingers being such that the flared ends of the blades will clear the projections on insertion of the blades in the housing.

3. An electrical connector for reception of a plurality of electrical plugs, comprising a housing of insulating material having openings for insertion of the plug blades, a plurality of contact members within the housing, each contact member having a terminal portion and a plurality of diverging spring fingers extending from the terminal portion in a plane substantially perpendicular to the plane of said terminal portion and leading from said portion toward the blade receiving openings, the two outer fingers extending at an angle to each other, projections within the housing that bear against said outer spring fingers adjacent to their connection with the terminal portion to clamp the contact members firmly in place by spring tension between said projections and the adjacent inner surface of an exterior wall of the housing, and posts within the housing at opposite sides of the terminal portion between which posts the terminal portion is located and held.
